(57) CLAIM

The ornamental design of a base for a floor cleaner, as shown and described.

DESCRIPTION

FIG. 1 is a top, front and right side perspective view of a base for a floor cleaner showing my new design;

FIG. 2 is a top, front and right side perspective view without the portion of the vacuum cleaner shown in broken lines of FIG. 1 thereof;

FIG. 3 is a top plan view thereof;

FIG. 4 is a front view thereof;

FIG. 5 is a right side elevational view thereof;

FIG. 6 is a left side elevational view thereof;

FIG. 7 is a rear view thereof; and,

FIG. 8 is a bottom view thereof.

The details shown in broken lines in FIGS. 1, 5, 6, 7 and 8 are for illustrative purposes only and form no part of the claimed design.
